Primary Examiner — Vy N Koenig(74) *Attorney, Agent, or Firm* — Womble Bond Dickinson (US) LLP(57) **CLAIM**

The ornamental design for a carton, as shown and described.

DESCRIPTION

FIG. 1 is a perspective view of a carton showing our new design.

FIG. 2 is a left elevation view of the carton of FIG. 1, the right elevation view is a mirror image.

FIG. 3 is a front elevation view of the carton of FIG. 1.

FIG. 4 is a rear elevation view of the carton of FIG. 1.

FIG. 5 is a top plan view of the carton of FIG. 1.

FIG. 6 is a bottom plan view of the carton of FIG. 1.

FIG. 7 is a perspective view of the carton of FIG. 1 shown in an open configuration; and,

FIG. 8 is a plan view of the carton of FIG. 1 shown in an unfolded configuration.

All evenly-spaced broken lines depict environmental subject matter only and form no part of the claimed design.
